UNITED STATES PATENT OFFICE.

THEODORE J. SCOFIELD, OF JACKSON, MICHIGAN, ASSIGNOR TO THE SPARKS-WITH-INGTON COMPANY, OF CLEVELAND, OHIO, A CORPORATION OF OHIO.

HORN.

Application filed August 7, 1922. Serial No. 580,262.

This invention relates to certain improvements in motor-driven horns adapted to be used as a signal or alarm for automobiles, motor boats, and similar machines.

The main object of the invention is to produce a simple, powerful and light motor horn at a considerably lower cost of manufacture than has heretofore been practiced, without sacrificing any of the advantages in this 10 class of horn.

Other objects and advantages relate to the details of form, construction and arrangement of the parts, all as will more fully appear from the following description, taken 15 in connection with the accompanying drawings, in which:

Figure 1 is a longitudinal section of the horn of my invention.

Figure 2 is a rear view of the horn with 20 the case and end plate removed.

Figure 3 is a view of the commutator brushes and the means for supporting the same in operative position.

Figure 4 is a front view of the horn with 25 the resonator and diaphragm removed.

Figure 5 is a sectional view of the rear diaphragm casing.

Figure 6 is a sectional view thru the post 30 and a commutator-supporting mechanism showing the spring permitting adjustment of the rear case, and the motor shaft.

Figure 7 is a sectional view thru the coil and its supporting cylinder.

The invention, as illustrated, comprises a 35 suitable diaphragm —1— having its marginal portion clamped between the base —2— of a front diaphragm case section —3— and the base of a rear diaphragm case section —4—, said sections and the diaphragm being secured in cooperative position in any suitable manner, as by screws —5— and co-operating nuts —6—.

The front diaphragm case section —3— 40 may carry in the usual manner a resonator —7— of any desired form and shape.

The rear diaphragm case section —4— is 45 preferably dished away from the diaphragm, as indicated in Figure 1, to form a diaphragm-vibrating chamber within which the actuator —8— rotates for contact with the wear piece —9— upon the diaphragm to effect vibration of the latter as the former is rotated. The case section —4—, as perhaps best indicated in Figure 5, has its cen-

tral portion —10— offset or pressed inwardly 55 toward the diaphragm and is formed at an eccentric point with an opening —11— provided with an inwardly projecting annular flange —12— constituting a bearing for the motor shaft —13— which carries the actuator —8— as heretofore referred to.

This off-set portion or cross bar —10— of the diaphragm case permits carrying of the bearing —11— forwardly of the plane of the rear wall of the section —4— and toward 65 the diaphragm, so that the armature —14— of the motor may be arranged in close proximity to the diaphragm, and perhaps partially within the case section —4—, and between the pole pieces —15— and —16—, 70 which may be, as shown, struck up from the case section —4— and project rearwardly therefrom, as hereinafter described.

The pole pieces —15— and —16— are 75 preferably of the arcuate form perhaps best illustrated in Figures 4 and 5, and are arranged upon opposite sides of the bearing —12— and comprise portions —17— integrally connecting the pole pieces to the base of the case section —4—. Each pole piece 80 includes a substantially straight extension, bracket or lug —18— and —19— respectively projecting laterally from the respective pole pieces and these extensions in substantially the same direction and in substantial parallelism with each other and with the cross bar —10— constitute bearing parts or brackets for the field coil —20— which is formed of insulated wire wound around a bar or cylinder —21— disposed between 90 the arms —18— and —19— and secured in position in any suitable way as by means of screws —22— projecting thru openings in the respective parts —18— and —19— and screwed into the interiorly threaded portion 95 of the tube or cylinder —21—.

By this means a rigid support for the field coil —20— —21— is provided and the pole pieces for the motor are materially strengthened by the rigid spacing and supporting 100 cylinder 21 —20—. The rear bearing for the motor shaft —13— is formed in a cup-shaped cover plate —25— which has a recessed or dished eccentric portion —60— which may be of circular form and covered 105 at its inner side by a disk —23— having its edge secured as by welding to the rear cover plate so as to constitute a rigid portion

thereof, and provided with a perforation or opening formed with a surrounding flange —24— constituting a bearing for the armature shaft. The shaft is adapted to contact 5 at its rear end with the inner surface of the dished portion —60— of the cap or closure —25— and its adjustment may be effected by moving said end cap or closure toward or from the diaphragm. The disk —23— may 10 be secured to the cap —25— in any suitable way, as by welding or otherwise. The support for the closure plate —25— is effected thru the medium of a pair of posts —62— and —63— of similar form and construction, and having their forward ends reduced and threaded and projected thru the base of the case section —4— so that the shoulder —61— at the reduced portion contacts with the outer surface of the case section —4— 15 and is secured in tight and rigid relation with respect to said section by means of nuts —28— and by this construction the posts become substantially rigid parts projecting from the case section —4— and have their 20 outer ends reduced and threaded and projected through the end cap —25— and secured in proper relation thereto by means of parts about to be described.

The post —62— may be provided with an 30 adjusting and stationing nut —30— threaded on the rear end of the post and adapted to be positioned upon the interior of the rear cap —25— so as to lock one side of the cap in a pre-determined position, while the 35 nut —29— threaded on the outer end of said post is adapted to contact with the outer surface of the cover plate to maintain the same in practically stationary position with respect to post —62—.

40 The opposite side of the cap is adjustably supported by means of a spiral spring —31— mounted on post —63— and positioned between the end cap —25— and the insulating block —32— also mounted on post —63— 45 and which, as hereinafter described, carries the commutator brushes —33— and —34— which are adapted to contact with the commutator —35— upon the armature shaft —13—. By adjusting nut —80— the cover 50 plate or rear cap —25— may be moved toward the diaphragm against the action of spring —31— thereby carrying the armature shaft forwardly to properly position the cam or actuator with respect to the dia- 55 phragm wear piece —9—.

For the purpose of holding the armature shaft against rattling, and at all times in 60 substantial contact with the interior of the end cap —25— a spring bar —33— is provided mounted upon one of the posts —62— or —63— at a point upon the interior of the case section —4— and between the case section and one of the nuts —28— and the bar 65 has its intermediate portion bent outwardly toward the diaphragm and its outer end par-

tion bent lengthwise across the actuator —8— and into contact with the end of the armature shaft —13— so as to press said armature shaft toward the interior of the end cap —25— to hold the same in proper 70 relation against rattling.

The post —63— upon which the spring —31— is mounted has as before stated, mounted thereon an insulating block —32— which rests against the shoulder —36— 75 upon the post —62— and is formed as shown in Figure 3, with an opening —37— adapted to fit upon the reduced rear portion of said post, and is held in position against shoulder —36— by means of the spring —31—, cap —25— and nut —70—. This insulating block is provided with a laterally extending conduit —38— internally threaded, as indicated by dotted lines in Figure 3, and carries the resilient flexible bars —39— for the 80 commutator brushes, and which bars have perforated end portions extending across the conduit —38— with their perforations in alignment with said conduit for the reception of retaining screws —40— which are 85 preferably spaced from the commutator bars —39— by means of U-shaped clips —41— having their flanged edges projecting laterally across the commutator bars —39— so as to maintain the same in proper position 90 when the screws —40— are tightened with relation to the insulating block —32—. The brushes —33— and —34— are preferably carried by the forward end of the bars —39— and may have their inner surfaces of 95 arcuate form to substantially fit the commutator, as indicated. The bars —39— in themselves constitute spring members tensioning to hold such brushes in contact with the commutator while effecting proper electrical relation.

The motor structure of the horn so far described is preferably encased within a cylindrical casing —42— which may be formed of a single sheet of metal bent into circular 100 form and having its longitudinal edges seamed or otherwise secured together to constitute a closed cylindrical case which is adapted to be fitted over the end cap —25— and brought into engaging relation with the 105 case section —4— which is shown as provided with a reduced shouldered portion —43— about which the casing —42— is adapted to tightly fit, and to which it may be secured in any suitable manner, as by 110 screws (not shown).

It will be noted that this construction of horn is of very simple character; that it may be formed and assembled in a comparatively small space, the pole pieces being 115 purposely formed from the rear diaphragm case section, although they may be formed separately therefrom and secured to the case section —4— in any suitable manner, as by 120 screws or welding. The forward armature 125

shaft bearing is formed in an inset cross bar integral with the rear diaphragm case section, and the entire supporting mechanism for the rear portion of the motor is provided thru the means of a pair of posts, one of which carries both commutator brushes and which posts are rigidly secured to the rear diaphragm case section. Novel means are provided for adjusting the motor shaft toward and from the diaphragm for effecting proper relation of the actuator with the wear piece —9—.

Although I have shown and described a specific structure, form and relation of the parts constituting a preferred embodiment of my invention, it will be obvious that all of the details are not inter-related, and that certain of the details of this invention may be combined with other forms of arrangement of parts, and in other relations, and that various changes and modifications may be made in the details of construction, form and arrangement of the parts, whether related or combined in a single structure, without departing from the invention as set forth in the appended claims.

I claim:

1. A horn comprising a case section, a pair of posts secured to said case section, and projecting therefrom, an end cap mounted on said posts, an armature shaft journaled in said case section and in said end cap, a commutator on said armature shaft, and a pair of commutator brushes carried by one of said posts for contact with said commutator.

2. A horn comprising a case section, a pair of posts secured to said case section and projecting therefrom, an armature shaft journaled in said case section, a commutator on said armature shaft, an insulating block mounted on one of said posts, a pair of spring arms carried by said insulating block, and a pair of brushes carried by said spring arm for contact with said commutator.

3. A horn comprising a case section, a pair of posts secured to said case section and projecting therefrom, an end cap mounted on said post, an insulating block mounted on one of said posts, a spring interposed between the insulating block and the end cap, an armature shaft journaled in the case section and end cap, a commutator on said armature shaft, and a pair of brushes carried by said insulating block for contact with said commutator.

4. A horn comprising a case section, a pair of posts secured to said case section and projecting therefrom, an end cap mounted on said post, an insulating block mounted on one of said posts, a spring interposed between the insulating block and the end cap, an armature shaft journaled in the case section and end cap, a commutator on said armature shaft, a pair of brushes carried by

said insulating block for contact with said commutator, and spring means tending to move the armature shaft toward the end cap.

5. A horn comprising a case section, a pair of posts secured to said case section and projecting therefrom, an end cap mounted on said post, an insulating block mounted on one of said posts, a spring interposed between the insulating block and the end cap, an armature shaft journaled in the case section and end cap, a commutator on said armature shaft, a pair of brushes carried by said insulating block for contact with said commutator, and a plate bearing against the forward end of said armature shaft and tending to move said shaft toward the end cap.

6. A horn comprising a case section having a pair of pole pieces struck up therefrom and integral therewith, a lug projecting laterally from each pole piece, a bar carried by the lugs and a field coil carried by said bar.

7. A horn comprising a case section, a diaphragm extending across the case section, pole pieces secured to the case section, ears projecting from the pole pieces in a direction substantially parallel with the diaphragm, a bar carried by the ears and a field coil carried by said bar.

8. A horn comprising a case section, a diaphragm extending across the case section, pole pieces secured to the case section, ears projecting from the pole pieces in a direction substantially parallel with the diaphragm, a cross bar connecting said ears, and a field coil mounted on said bar.

9. A horn comprising a front case section, a cup-shaped rear case section, a diaphragm having its marginal portion clamped between said case sections, said rear case section provided with pole pieces struck up therefrom and integral therewith, and forming a cross bar, and an armature shaft having a bearing with said cross bar.

10. A horn embodying a cup-shaped diaphragm case section having a part of its bottom portion offset forwardly, an armature shaft having a bearing in said forwardly offset portion, an armature mounted on said shaft in such a position that a portion of the armature is forward of the plane of said bottom portion of the diaphragm case section, and pole pieces struck up from said bottom portion at opposite sides of the forwardly offset portion.

11. A horn embodying a cup-shaped diaphragm case section having a part of its bottom portion offset forwardly, an armature shaft having a bearing in said forwardly off-set portion, an armature mounted on said shaft in such a position that a portion of the armature is forward of the plane of said bottom portion of the diaphragm case

section, pole pieces struck up from said bottom portion at opposite sides of the forwardly offset portion, lugs extending laterally from the pole pieces, and a field coil carried by said bar.

12. A horn comprising an armature shaft having a commutator mounted thereon, a case section formed with a bearing for said armature shaft, and a post carried by said case section, an insulating block mounted on said post, a pair of spring arms carried by said block, and a brush mounted upon each of said spring arms for contact with said commutator.
13. A horn comprising a case section, a pair of posts secured to said case section and projecting rearwardly therefrom, an end cap mounted on said posts, one of said mountings being adjustable, an armature shaft having one end journaled in said cas-

ing and its other end having a thrust bearing in said end cap, means for adjusting the cap along one of said posts, and spring means tending to move a portion of said cap in a direction away from said case section.

14. A horn comprising a case section, a pair of posts secured to said case section and projecting rearwardly therefrom, an end cap mounted on said posts, one of said mountings being adjustable, an armature shaft having one end journaled in said casing, and its other end having a thrust bearing in said end cap, means for adjusting the cap along one of said posts, and spring means tending to move said armature shaft toward said end cap.

In witness whereof I have hereunto set my hand this 29th day of July, 1922.

THEODORE J. SCOFIELD.
